UNITED STATES PATENT OFFICE.

MORRIS P. BRAY, OF NEW HAVEN, CONNECTICUT.

CORSET.

SPECIFICATION forming part of Letters Patent No. 275,982, dated April 17, 1883.

Application filed January 29, 1883. (No model.)

To all whom it may concern:

Be it known that I, MORRIS P. BRAY, of New Haven, in the county of New Haven and State of Connecticut, have invented a new Improvement in Corsets; and I do hereby declare the following, when taken in connection with accompanying drawings and the letters of reference marked thereon, to be a full, clear, and exact description of the same, and which said drawings constitute part of this specification, and represent, in—

Figure 1, a rear view of the two parts of the back; Fig. 2, a transverse section of the same enlarged.

This invention relates to an improvement in corsets, with special reference to the back or lacing edges.

In the more general construction of corsets a series of eyelets are introduced at the rear edge of the two parts of the back and the lacing run through from side to side. This arrangement brings the lacing upon both the inside and outside of the corset, creating an unevenness upon the inside, disagreeable and uncomfortable to the wearer.

The object of my invention is to provide a substitute for the eyelets, which will permit the lacing to be made entirely upon the outside of the corset, so that the inside will be plain, flush, and smooth throughout; and it consists in the construction as hereinafter described, and more particularly recited in the claims.

A represents the one part, and B the other part, of the back portion of a corset. Instead of the two thicknesses *a b* being brought together at the extreme edge, in the usual manner, the under thickness comes to the edge, and the upper thickness at a little distance back, as at *d*. (See Fig. 2.) Between the edge *d* of the thickness *a* and the inner thickness, *b*, I introduce a strip, *e*, of sufficient width to extend to the edge, and, with the inner thickness, *b*, complete that edge. At the edge of the parts, and between the strip *e* and the thickness *b*, I introduce one end, *f*, of a piece of narrow tape, *h*, or other suitable material, turning the piece *h* outward, and onto the part of the corset, introducing the other end, *i*, beneath the edge *d* of the outer thickness, *a*, as seen in Fig. 2. These pieces *h* are introduced at in-

tervals, leaving a space, say, substantially equal to the distance between the eyelets of an ordinary lacing, or may be more or less. These pieces form loops *l* upon the outside of the parts and at the extreme rear edge, through which the lacing *m* is introduced, as seen in Fig. 1—that is, first through one loop on one side, then through the next loop on the opposite side, and so on, alternating from side to side, as shown, the lacing being drawn up and secured in the usual manner. By this construction the inner side of the corset is left smooth and without any of the unevenness and discomfort arising from the usual eyelet-lacing.

Instead of inserting the end *i* of the loops beneath the rear edge of the outer section and applying the strip *e*, which I prefer, because it gives to the corset the most finished appearance, the two thicknesses *a b* may extend to the extreme edge in the usual manner, and the end *f* of the piece *h* introduced between the two thicknesses at the edge, the other edge, *i*, turned back upon the outside and stitched directly to the two thicknesses.

The space between the line where the end *i* of the loops is secured and the edge of the corset forms a pocket for a steel or stay, *n*, and while I prefer this stay, because it forms a comfortable support for the back, it may be introduced at some other point or omitted altogether.

I claim—

1. The herein-described improvement in corsets, consisting of the loops *l*, formed by narrow pieces *h*, introduced at intervals; one end, *f*, of the loop between the two thicknesses of the corset at the edge, the other end turned outward onto that part of the corset and secured thereto, substantially as described.

2. In a corset, the back or lacing section composed of two thicknesses, *a b*, the inner thickness extending to the extreme edge of the part, the outer thickness left back from the edge, combined with a strip, *e*, one edge of which is introduced between the rear edge of the outer thickness, *a*, and the thickness *b*, its front edge meeting the edge of the inner thickness, with loops *l* at intervals, one end, *f*, of each loop introduced between the two thicknesses at the edge and extending backward, its other end

inside the thickness a and there secured, substantially as and for the purpose described.

3. The herein-described improvement in corsets, consisting of the loops l , formed by narrow pieces h , introduced at intervals, one end, f , of the loop between the two thicknesses of the corset at the edge, the other end turned outward onto that part of the corset and se-

cured thereto, with a stay, n , in the pocket, between the edge of the part and the line where the loops are secured, substantially as described.

MORRIS P. BRAY.
